[57] CLAIM

The ornamental design for a toaster oven cast broiling grill, as shown and described.

DESCRIPTION

FIG. 1 is a perspective view of the invention;
FIG. 2 is a top plan view of the invention;
FIG. 3 is an end view of the invention, the opposite end view being a mirror image;
FIG. 4 is a front view of the invention, the back view being a mirror image;
FIG. 5 is a bottom view of the invention;
FIG. 6 is a cross-sectional view of the invention as viewed along section line 6—6 of FIG. 1; and,
FIG. 7 is a cross-sectional view of the invention as viewed along section line 7—7 of FIG. 1.
The broken line showing of a cross section of a pan in FIGS. 6 and 7 is for illustrative purposes only and forms no part of the claimed design.
